STEAM LOCOMOTIVE ADMISSION AND EXHAUST PISTON VALVES

Thomas J. Hoy, Newark, N. J.

Application January 17, 1947, Serial No. 722,731

12 Claims. (Cl. 121—124)

1

This invention relates to valves and valve gear for steam locomotives, reciprocating steam engines and the like and more particularly to the admission of steam to and the exhaustion of steam from the power cylinder or cylinders thereof.

The present invention provides apparatus through which the rate of flow of steam to and the rate of flow of steam from the power cylinder or power cylinders of a steam locomotive, reciprocating steam engine or the like is controlled in relationship to each other at a predetermined rate.

The present invention also provides a reciprocating steam engine, locomotive or the like having separate admission and separate exhaust valves.

This invention further provides apparatus through which the volume of steam flowing to and the volume of steam flowing from the power cylinder or power cylinders of a steam locomotive, reciprocating steam engine or the like having separate admission and separate exhaust valves is greatly increased.

The invention will be understood from the following description when considered in connection with the accompanying drawings forming a part thereof and in which:

Fig. 1 is a fragmentary longitudinal sectional view of an admission piston valve for steam locomotives, reciprocating steam engines and the like of the present invention.

Fig. 1A is an end view of the piston shown in Fig. 1 taken from the right of Fig. 1;

Fig. 2 is a fragmentary longitudinal sectional view of an exhaust piston valve for steam locomotives, reciprocating steam engines and the like of the present invention;

Fig. 3 is an enlarged transverse sectional transverse sectional view taken on the line 3—3 of Figs. 4 and 5 through the valve bushing ports and the cylinder bushing port with the piston valve ends shown;

Figs. 4 and 5 are longitudinal sectional views of the exhaust and of the piston valves of Figs. 2 and 1 respectively showing the valves associated with a cylinder having a piston therein and taken on the lines 4—4 and 5—5 respectively of Fig. 3;

Fig. 6 is an elevational view on a reduced scale taken on the line 6—6 of Fig. 7;

Fig. 7 is a view similar to Fig. 3 taken on line 7—7 of Fig. 4 but with the valve and bushings removed from the piston valve cylinders;

Fig. 8 shows a compound radius rod drive for actuating the admission and exhaust valves;

2

Fig. 9 illustrates one type of valve gear connected to the radius rod of Fig. 8 to operate the radius rod and for actuating the admission and exhaust valves.

Fig. 10 shows a modified valve crosshead drive; Figs. 11 and 12 are views similar to Figs. 1 and 2 respectively but of another form of the invention, and

Figs. 13 and 14 are views similar to Figs. 11 and 12 respectively but of another form of the invention.

Like characters of reference refer to like parts throughout the several views.

Referring to the drawings, the reference character 15 designates a housing having a live steam chest 16 in the upper part and at one side thereof and an exhaust steam chamber 17 also in the upper part but on the opposite side thereof. The steam chest 16 and chamber 17 are disposed above a cylinder 18 having a bushing 19 therein and are separated therefrom by a dividing wall 20 (Fig. 7) which, as shown, is an integral part of the housing. The chest 16, chamber 17 and cylinder 18 all extend longitudinally of the housing

25 15. The live steam chest 16 is in communication at one end thereof with the adjacent end of the cylinder 18 through a port 21 in the upper part of the bushing 19 of cylinder 18 (Fig. 3), the port 21 in turn communicating with a circumferential groove 22 in the peripheral wall of the steam chest through a transverse passage 23 in the housing 15 (Fig. 2) and a plurality of ports 24 in a bushing 25, hereinafter described, in the steam chest. At the opposite end thereof, the chest 16 is in communication with cylinder 18

30 35 through a port 26 in the upper part of the bushing 19 of cylinder 18, the port 26, like the port 21 communicating with a circumferential groove 27 in the peripheral wall of the chest 16 through a passage 28 similar to the passage 23 and a plurality of ports 29 in a bushing 38 in the steam chest. The opposite ends of the chest 16 have circumferential offset end portions 30 and 31 respectively of greater diameter than the remainder of the cylinder. A steam inlet passage 32 extends longitudinally within the peripheral wall of the chest 16 at the upper part thereof and at opposite ends communicates with the offset portions 30 and 31 and centrally thereof com-

40 45 50 municates with a steam inlet pipe 33. A centrally disposed steam distributing passage 34 (Fig. 5) extends circumferentially of the steam chest 16 in the peripheral wall thereof and is in communication with the interior of the chest at

55 points centrally of the opposite ends of the chest

through an inlet port 35 at the top of the chest and another inlet port 36 at the bottom of the chest.

The steam chest 16 has cylindrically-shaped bushings 25 and 38 secured therein at opposite ends thereof said bushings being spaced apart to form a space therebetween in the central portion 39 of the chest. The bushings 25 and 38 overhang the offset portions 30 and 31 respectively and have spaced inlet ports 40 and 41 in them respectively. The inlet ports 40 and 41 communicate respectively with the offset portion 30 and 31.

Admission piston valves 42 and 43 slidably engage the inner periphery of the bushings 25 and 38 and are sealed against leakage by piston rings 44 and 45. The valves are fixedly mounted on a piston rod 46 and held in spaced relationship to one another by a sleeve 47. The valves 42 and 43 are cylindrically-shaped and have a cylindrically-shaped passage 48 extending longitudinally therein. The passage 48 has a sleeve 49 therethrough which sleeve is of smaller diameter than the passage 48 and is held within the valve by webs 50 (Fig. 1A). The sleeve 49 is secured to valve stem 46 by nut 51. The outer peripheries of the valves 42 and 43 are concave as shown at 52, Fig. 1, the concave surface extending longitudinally of the valve from closely adjacent one end to closely adjacent the opposite end thereof. The width of the piston valves is such that they will, during a cycle of their movement, overlap the ports 24 and 29 respectively to prevent steam from entering said ports and thereafter will respectively bring the ports 24 and 40 and 29 and 41 into communication through the concave portions 52 respectively of each of the valves while at the same time bringing the central portion 39 of the steam chest into communication with the passages 22 and 27 and with the ports 24 and 29. The spacing of the valves 42 and 43 on the stem 46 and the extent of the reciprocal movement of the stem is such that when the valve 42 overlaps the port 24 the valve 43 is so positioned that the ports 29 are in communication with the central portion 39 of the chest. Also, at this position, ports 29, groove 27, passage 28 and port 26 are in communication through the concave portion 52 of the valve 43 and when the valve 43 is so positioned as to overlap the port 29, the valve 42 is in such position that the ports 21, passage 23, groove 22 and ports 24 are in communication through the concave portion 52 of valve 42 with the offset end portion 31 and also in communication with the central portion 39.

The exhaust chamber 17 (Fig. 4) is surrounded by a peripheral wall 54 the end portions of which wall are of lesser diameter than the central portion to thereby form opposite end portions 55 and 56 which are of lesser diameter than the central portion 57. The central portion 57 has an outlet port 58 through the side wall thereof while the end portion 55 and the end portion 56 have exhaust ports 59 and 60 respectively through said side wall. The exhaust ports 58, 59 and 60 each communicate with a separate exhaust outlet conduit 61 which outlet conduits terminate in a single conduit, not shown.

Cylindrically-shaped bushings 62 and 63 are secured in spaced relationship to one another in the exhaust chamber 17 adjacent opposite ends of the chamber. The bushings overhang into the central portion 57 of the chamber 17 and have a plurality of ports through the overhanging portions, the bushing 62 having ports 53

therethrough while bushing 63 has ports 64 therethrough. The bushing 62 also has ports 65 extending therethrough and spaced from ports 53, the ports 65 being in communication with a circumferential groove 66 in the inner peripheral wall of the chamber 17 and transverse passage 28 which passage in turn communicates with exhaust port 61 through the bushing 19 of cylinder 18 at the top thereof while ports 68 of bushing 63 are in communication with the circumferential groove 69 in the inner peripheral wall of the chamber 17 which groove communicates with forward exhaust port 10 in the bushing 19 of cylinder 18 at the upper part thereof through the transverse passage 23.

Exhaust piston valves 71 and 72 are slidably mounted for reciprocal movement in the bushings 62 and 63 in chamber 17 and are sealed against leakage by piston rings 73 and 74. The valves are fixedly mounted on piston rod 75 and held in spaced relationship to one another on the piston rod by a sleeve 76. These valves are cylindrically-shaped and the outer peripheries of the valves are concave, as shown at 77 and 77', Fig. 2, the concave surface extending longitudinally of the valve from closely adjacent one end thereof to closely adjacent the other end. The width of the piston valves is such that they will, during a cycle of their movement, overlap the ports 65 and 68 respectively, preventing steam from exhausting from the cylinder 18 through said ports and thereafter will respectively bring the ports 65 and 53 and 64 and 68 into communication through the concave portions 77 and 77'. The spacing of the valves 71 and 72 on the stem 75 and the extent of the reciprocal movement of the stem is such that when the valve 71 overlaps the ports 65 and 63 the valve 72 is so positioned that the ports 68 communicate with the end zone 56 and also with the central portion 57 through the ports 68 and 64 and likewise when the valve 72 overlaps the ports 64 and 68 steam will exhaust from the cylinder 18 through the port 67, passage 28 and ports 65 into the end portion 55 and also into the central portion 57 through the ports 65, concave portion 77' and port 53.

The cylinder 18 has a piston 78 slidably mounted therein for reciprocal movement, piston 78 being sealed against leakage by piston rings 79. Piston 78 has a forward surface 80 and a rearward surface 81 and is fixedly mounted on the piston rod 82.

In operation, the admission steam piston valves 42 and 43 and the exhaust piston valves 71 and 72 may be actuated by any well-known form of valve gear and reverse gear. The admission valves and exhaust valves are so actuated in relationship to one another that when steam is admitted to the cylinder at one end thereof, steam will be exhausted through the ports at the end of the cylinder opposite that at which the steam enters. For example, when the piston 78 is positioned at the extent of its movement to the right, admission valve 42 is in the position indicated in Fig. 1 so that steam from the steam conduit 33 will flow through inlet port 35 (Fig. 5) into central portion 39 thence through ports 24 and groove 22 into transverse passage 23 whence the steam passes through ports 21 and 70 in the bushing 19 in cylinder 18 into said cylinder. Steam from central portion 39 also flows into the cylinder through passages 48 into end portion 30, thence into ports 40 thereafter to flow through the concave passage 52 in the periphery of the valve 75 into and through the ports 24. From ports

24 the steam flows together with steam flowing into the ports 24 directly from the central portion 39, as aforesaid, into the transverse passage 23 then to the cylinder through ports 21 and 70. The steam flows into cylinder 18 through said ports to move the piston 78 to the left, Fig. 5. As the piston moves to the left, admission piston valve 43 is so positioned as to overlap the ports 29 so that steam is not permitted to enter the ports 29, passage 28 and port 26 at the end of the cylinder 18 opposite that at which the port 21 is positioned. Also, when the cylinder is at its extreme right hand position the exhaust valves 71 and 72 are so positioned that the valve 72 overlaps the ports 68 thereby preventing the exhausting of steam from the cylinder through ports 68, passage 23 and ports 21 and 70, while exhaust valve 71 is so positioned that ports 67 and 26 are in communication with the end zone 55 through transverse passage 28, groove 66 and ports 65, whence the steam is exhausted from said end zone 55 through port 59. Steam from ports 67, 26 and passage 28 also passes from ports 65 through concave passage 77 and ports 53 into central zone 57 whence the steam is exhausted through outlet port 58. When the piston 78 reaches the extent of its movement to the left, Fig. 5, the admission piston valves are moved so that valve 42 overlaps ports 24 preventing further steam from entering the cylinder 18, while exhaust valve 72 is moved to such position that the ports 10 and 21 are in communication through transverse passage 23 and ports 68 with the end portion 56 of the exhaust chamber and with the central portion 57 thereof through ports 64 and concave portion 77 in the periphery of the valve. Steam from end portion 56 and central portion 57 is exhausted through outlet ports 60 and 58 respectively. At the same time, admission valve 43 is so moved that it is positioned to permit steam from the steam conduit 33 to flow from inlet passage 32 and ports 35 and 36 into central portion 39, then through ports 29 and groove 27 into transverse passage 28 whence it passes into the cylinder 18 through ports 26 and 67. Steam also will flow through passage 32 into end portion 31, thence into ports 26 and 67 through ports 41, concave portion 52 and ports 29 whence it flows to ports 26 and 67 with the steam from central portion 39 as aforesaid. Exhaust valve 71 will at this time overlap the ports 67 preventing steam from exhausting therethrough into transverse passage 28 and port 67.

With the apparatus of the present invention, the admission ports through which steam is admitted to the power cylinder and the exhaust port through which steam is exhausted from the power cylinder may be of different sizes. Also the admission piston valves may be of the same or of different diameter than the exhaust piston valves. For example, in a typical installation the admission valves 42 and 43 may be 9" in diameter with a net circumference of 22". The port openings 24 or 29 would be $2\frac{1}{8}$ " and the openings 24 or 29 would have a total area of 60 square inches. Valve travel of the valves 42 and 43 would be $4\frac{1}{2}$ " and the valves would overlap ports 24 or 29 by $\frac{3}{2}$ " when closing said ports. The exhaust valves 71 and 72 may be of a diameter of 9" and have a net circumference of 22" while port openings 65 or 68 would be $4\frac{1}{4}$ " with a total area of $93\frac{1}{2}$ square inches. Total exhaust valve travel would be $4\frac{1}{4}$ ". The above dimensions and sizes are given by way of example and

are not to be understood as limiting the invention thereto.

In the embodiment of the invention disclosed in Figs. 11 and 12, the admission valves 42 (Fig. 11) and 43 and the exhaust valves 71 (Fig. 12) and 72 respectively control an additional port through which, in the case of admission valves, live steam passes to the cylinder 18 and, in the case of the exhaust valves, an additional port through which exhaust steam flows from the cylinder.

As shown in Fig. 11, the piston 42, instead of having a concave portion 52 as shown in Fig. 1, has an elongated portion 100 of lesser diameter than the outside diameter of the piston which portion extends longitudinally of the piston intermediate the opposite ends thereof to form a passage 101. Adjacent the forward end of the piston, a port control section 102 is secured to the piston by webs 103 which section has a longitudinal passage 104 therethrough communicating with passage 101. The section 102 is spaced from the forward end of the piston to form an inlet passage 105 which communicates with longitudinal passage 104 and ports 40 in the part of bushing 25 which overhangs end portion 30 of steam chest 16. Ports 40 extend through the overhanging part of sleeve 25 at a point intermediate ports 24 and 49 and communicate with passage 101 and end portion 30. Section 102 of valve 42 controls the ports 40. The admission valve 43 in this embodiment of the invention would be of a construction similar to that of valve 42. In the operation of the admission valve 42 of Fig. 11, steam from the end portion 30 of the steam chest flows through ports 40, inlet passage 105, longitudinal passages 104 and 101 and ports 40' and passage 101 to enter the cylinder 18 through ports 24, peripheral groove 22, transverse passage 23 and ports 21 and 70. The flow of steam into ports 40' is controlled by section 102 while the flow of steam through ports 40 is controlled by the forward end section 42' of piston 42.

45 The exhaust piston valve 72, as shown in Fig. 12, instead of having a concave portion 67 as shown in Fig. 2, has an elongated portion 106 of lesser diameter than the outside diameter of the piston which portion extends longitudinally of the piston intermediate the opposite ends thereof to form a passage 107. A port control section 108 is secured to the portion 106 adjacent the rearward end of the piston by webs 109. The section 108 has a passage 110 therethrough which passage communicates with longitudinal passage 107. The section 108 is spaced from the rearward end of the piston to form an outlet passage 111 which communicates with passage 110 and exhaust ports 64 in the part of bushing 63 which overhangs central portion 57 of exhaust chamber 71. Exhaust ports 64 extend through the overhanging part of the sleeve 63 at a point intermediate ports 64 and 68 and communicate with passage 107 and central portion 57. Section 108 of valve 72 controls ports 64'. The construction of valve 71 of this embodiment of the invention would be similar to that of valve 72. In the operation of exhaust valve 72 of Fig. 11 steam from cylinder 18 exhausts through ports 21 and 70 in the cylinder bushing 19 therinto into transverse passage 23 whence it flows through ports 68 into end portion 56 of the exhaust cylinder and into central portion 57 thereof. The flow to central portion 57 is from passage 23 through ports 68, passage 107 whence

a part of the steam exhausts through ports 64' into the central portion 57 of the exhaust cylinder while another part of the steam flows through passage 110 in section 108 into passage 111 thence through ports 64 into the central portion 57. The exhausting of steam through ports 64' is controlled by section 108 while the exhausting of steam through ports 64 is controlled by the rearward end of piston valve 72.

As shown in Figs. 11 and 12, the exhaust 72 is of greater diameter than the admission piston valve 42 and the exhaust ports 64, 64' and 68 have a greater area than admission ports 24, 40' and 48.

In the embodiment of the invention shown in Figs. 13 and 14, which is somewhat similar to the form shown in Figs. 11 and 12, the admission valves 42 (Fig. 13) and 43 and the exhaust valves 71 (Fig. 14) and 72 respectively control an additional port at the end of the valve opposite that on which the ports are positioned in the form of the invention disclosed in Figs. 11 and 12, and through which, in the case of the admission valves, live steam passes to cylinder 18 and, in the case of the exhaust valves, through which steam is exhausted from the cylinder.

As shown in Fig. 13, the admission piston valves 42 is somewhat similar to the piston 42 of Fig. 11 but has an additional elongated portion 112 of a lesser diameter than the outside diameter of the piston which extends from the inner end of the piston toward the interior of the steam chest 16. Elongated portion 109 has a port control section 113 secured to the portion 112 by webs 114 which section has a central passage 115 extending longitudinally therethrough. Section 113 is spaced from end 116 of the valve to form an outlet passage 117 which communicates with groove 22 through port 24. Port 24' in bushing 25, which is spaced inwardly toward the interior of steam chest, communicates with groove 22 through a passage 118 and is controlled by section 113. The operation of admission valve 42 of Fig. 13 is similar to that shown in Fig. 11 except that when the valve is open steam also flows from the interior of the steam chest through port 24', passage 118 and passages 115, 117 and port 24 into peripheral groove 22 whence it passes to transverse passage 23 into cylinder 18 through ports 21 and 70.

Exhaust piston valve 72, as shown in Fig. 14, is somewhat similar to the exhaust valve shown in Fig. 12 but has an elongated portion 119 projecting outwardly therefrom at the end thereof which is adjacent port 68. Portion 119 is of a diameter less than the outside diameter of the valve and has a port control section 120 secured thereto by webs 121. Section 120 has a central passage 122 extending longitudinally therethrough which is in communication with port 68 through passage 123 adjacent the end of the valve. Port 124, spaced outwardly from port 68 and groove 69, is in communication with groove 69 through passage 125 and is controlled by section 120. The operation of exhaust valve 72 of Fig. 14 is similar to valve 72 of Fig. 12 except that when the valve 72 of Fig. 14 is in an open position steam from piston 18 exhausting through groove 69 also flows through passage 125 and port 124 into section 56 and from port 68 also flows through passages 123 and 122 into section 56 of exhaust chamber 17 whence it passes outwardly thereof through exhaust port 60.

As shown in Fig. 4, valve gear is connected to the exhaust piston valve rod 75 through cross-

head 84 having an opening which receives a pin 85. Connected to the crosshead by pin 85 is a combination movement lever which in turn is coupled to and driven by the locomotive crosshead, not shown. Admission radius rod 86 is connected to the combination lever at the opposite end by pin 87. The individual crossheads 84 and 88 are driven in common guides by a combination lever pin 89 which also passes through the opening in cross head 84. With such an arrangement, both the exhaust and admission valves have the same amount of travel and may be associated with any well-known single action valve gear.

The admission and exhaust valves may be operated from valve gear including a Walschaert link 89, as shown in Fig. 9, which includes a link block 90, reverse shaft 91 together with reverse arm 92 and a lifting rod 93 and eccentric rod 94. These parts transmit movement from a locomotive crank pin and reverse gear, not shown, and operate radius rod 86 (Figs. 8 and 9) which is connected to the admission valve actuating mechanism as hereinbefore described and also actuates the exhaust valves 71 and 72 through the radius rod 95 (Fig. 8) which is slidably mounted on the bearing member 96 of the rod 86 and held in position by pin 97.

A further form of valve gear may be used in which the individual crossheads are on individual guides, as shown in Fig. 10, the admission valves 42 and 43 being driven from radius rod 86 and 95 through two duplicate combination lever assemblies. The exhaust piston valves 71 and 72, as shown in Fig. 10, is driven by valve gear radius rod 95. This rod is flexibly attached to radius rod 86 and movable on bearing member 96, as shown in Fig. 8. Rod 95 drives valves 71 and 72 through a combination lever assembly positioned on and driven from the inside or front end of a locomotive cross head, not shown. The exhaust valve combination lever short arm may be longer than the admission valve combination lever short arm. This will provide a longer period of exhaust port opening, a later release and later compression at the running cut-off positions of the reverse lever.

While the various valve constructions of the present invention have been shown and described as controlling the flow of steam into and the flow of steam exhausted from the power cylinder of a steam locomotive, reciprocating steam engine or the like, it will be understood that said valves may be used for controlling the flow of a fluid in general.

Changes may be made in the form, location and arrangement of the several parts of the apparatus disclosed without departing from the principles of the invention. Accordingly, the invention is not to be limited excepting by the scope of the appended claims.

What is claimed is:

1. In a reciprocal steam engine, locomotive or the like having a cylinder with a piston positioned in the cylinder for reciprocal movement, means providing separate steam admission and steam exhaust chambers, said admission and exhaust chambers having an end chamber portion adjacent each end thereof and an intermediate chamber portion intermediate said end portions, each of said separate chambers having a plurality of ports in communication with the cylinder, said ports respectively being positioned in spaced relationship with the opposite ends of said chambers and so as to communicate with said intermediate chamber portions and the end

chamber portion adjacent said ports, the intermediate portion and each end of the steam admission chamber being in communication with a source of steam and the intermediate portion and each end portion of the exhaust chamber being in communication with a steam exhaust, admission piston valves operable in the steam admission chamber, one of said valves being associated with the ports of the admission chamber at one end of said piston stroke and another of said valves being associated with the ports of the admission chamber at the opposite end thereof so as to control the admission of steam from said intermediate and end portions of the admission chamber, and exhaust piston valves operable in the steam exhaust chamber, one of said valves being associated with the ports of the exhaust chamber at one end of said piston stroke and another of said valves being associated with the ports of the exhaust chamber at the opposite end thereof so as to control the exhaustion of steam from said intermediate and end portions of the exhaust chamber into the cylinder.

2. In a reciprocal steam engine, locomotive or the like having a cylinder with a piston positioned in the cylinder for reciprocal movement, means providing separate steam admission and steam exhaust chambers, said admission and exhaust chambers having an end chamber portion adjacent each end thereof and an intermediate chamber portion intermediate said end portions, each of said separate chambers having a plurality of ports in communication with the cylinder, said ports respectively being positioned in spaced relationship with the opposite ends of said chambers and so as to communicate with said intermediate chamber portion and the end chamber portion adjacent said ports, the intermediate portion and each end of the steam admission chamber being in communication with a source of steam and the intermediate portion and each end portion of the exhaust chamber being in communication with a steam exhaust, each end of the stroke of said piston, admission piston valves operable in the steam admission chamber, one of said valves being associated with the ports of the admission chamber at one end of said piston stroke and another of said valves being associated with the ports of the admission chamber at the opposite end thereof, exhaust piston valves operable in the steam exhaust chamber, one of said valves being associated with the ports of the exhaust chamber at one end of said piston stroke and another of said valves being associated with the ports of the exhaust chamber at the opposite end thereof, valve actuating means associated with the admission piston valve, and other valve actuating means associated with the exhaust piston valve, said actuating means reciprocating the admission valves to open and close the ports with which said valves are associated, said other actuating means reciprocating the exhaust valves to open and close the ports with which said valves are associated.

3. In a reciprocal steam engine, locomotive or the like having a cylinder with a piston positioned in the cylinder for reciprocal movement, means providing separate steam admission and steam exhaust chambers, said admission and exhaust chambers having an intermediate chamber portion and an end chamber portion communicating with the intermediate portion and adjacent one end of the chamber, each of said separate chambers being in communication with the cylinder adjacent opposite extremities of the

stroke of the piston through a port positioned in spaced relationship with said one end of the chamber and so to communicate with said intermediate and end chamber portions, the intermediate chamber portion and the end of the steam admission chamber being in communication with a source of steam and the intermediate chamber portion and the end chamber portion of the exhaust chamber being in communication with a steam exhaust, an admission piston valve operable in the steam admission chamber, an exhaust piston valve operable in the exhaust steam chamber, said valves respectively being adapted to control the passage of steam from the end chamber portion adjacent the admission valve and the intermediate chamber portion of the admission chamber to the cylinder and the passage of steam from the cylinder to the end chamber portion adjacent the exhaust valve and the intermediate chamber portion of the exhaust chamber, and valve actuating means cooperating with the valves and operable by said piston, the valve actuating means being so constructed and arranged as to move the valves into an open position to permit communication or into a closed position to prevent communication between their respective chambers and the cylinder during a relatively short distance of the total travel of the piston between said extremities.

4. In a reciprocal steam engine, locomotive or the like having a cylinder with a piston positioned in the cylinder for reciprocal movement, means providing separate steam admission and steam exhaust chambers said admission and exhaust chambers having an end chamber portion adjacent each end thereof and an intermediate chamber portion intermediate said end portions, the steam admission chamber having steam outlet ports, said outlet ports communicating with the cylinder adjacent opposite extremities of the stroke of the piston, an admission valve associated with the outlet port at one end of said piston stroke, another admission valve associated with the outlet port at the opposite end of said piston stroke, means for moving said valves into a closed and an opened position in relationship to the outlet ports, said valves being spaced apart and from the opposite ends of the chamber, said end chamber portions and said central chamber portion being in communication with a steam inlet, the admission valves being constructed to close the outlet ports when moved to a closed position and to bring the central chamber portion and the end chamber portions into communication with the outlet ports when moved to an opened position, said exhaust chamber being in communication with the cylinder adjacent the opposite extremities of the piston stroke through exhaust ports, an exhaust valve associated with the outlet port at one end of said piston stroke, another exhaust valve associated with the outlet port at the opposite end of said piston stroke, and means for reciprocating said valves into a closed and into an opened position in relationship to the exhaust ports, said valves being spaced apart and from the opposite ends of the chamber, the end chamber portions and the central chamber portion each having a steam outlet, the exhaust valves being constructed to close the exhaust ports when moved to a closed position and to bring the central chamber portion and the end chamber portions into communication with the exhaust ports when moved to an opened position.

5. Valve apparatus for admitting steam to the

cylinder of a reciprocal steam engine, locomotive or the like having a reciprocating piston in said cylinder, the valve apparatus comprising a cylindrical chamber having a peripheral wall with a longitudinal passage therein communicating with opposite end portions of the chamber, steam inlet means in communication with said passage and with the chamber intermediate the opposite ends thereof, the cylinder having steam outlet ports, said outlet ports communicating with the cylinder adjacent opposite extremities of the stroke of said piston, a piston valve rod arranged for reciprocal movement in the chamber, bushing means in said chamber adjacent opposite ends thereof and having longitudinally spaced ports therethrough one of said ports being in communication with a steam outlet port and the central portion of the chamber and another of said ports being in communication with an end portion of the chamber, cylindrically-shaped admission valves mounted in spaced relationship to one another on the piston valve rod to move therewith and respectively slidably engage one of said bushings in a fluid-tight manner, the valves having a concave peripheral portion, said peripheral portion being of such length that when the valves are in their closed position the concave portion overlaps said one of the spaced ports only and when the valves are in their open position said one port is in communication with the intermediate portion of the chamber and with said other port of the longitudinally spaced ports through said concave peripheral portion of the valve so that steam will flow from the end portions and from said intermediate portions of the chamber to said outlet ports.

6. Valve apparatus for admitting steam to the cylinder of a reciprocal steam engine, locomotive or the like having a reciprocating piston in said cylinder, the valve apparatus comprising a cylindrical chamber having a peripheral wall with a longitudinal passage therein communicating with opposite end portions of the chamber, steam inlet means in communication with said passage and with the chamber intermediate the opposite ends thereof, the cylinder having steam outlet ports, said outlet ports communicating with the cylinder adjacent opposite extremities of the stroke of said piston, a piston valve rod arranged for reciprocal movement in the chamber, bushing means in said chamber adjacent opposite ends thereof and having a plurality of longitudinally spaced ports therethrough, one of said spaced ports being in communication with a steam outlet port and the central portion of the chamber and at least two other of said longitudinally spaced ports being in communication with an end portion of the chamber, cylindrically-shaped admission valves mounted in spaced relationship to one another on the piston valve rod to move therewith and respectively slidably engage one of said bushings in a fluid-tight manner, the valves having passages so arranged that when the valves are in closed position the valves overlap said one of the spaced ports and the passages are out of communication with the outlet ports and when the valves are in their open position said one port is in communication with the intermediate portion of the chamber and with said other ports of the longitudinally spaced ports through said valve passages so that steam will flow from the end portions and from said intermediate portion of the chamber to said outlet ports.

7. Valve apparatus for exhausting steam from the cylinder of a reciprocal steam engine, loco-

otive or the like having a reciprocating piston in said cylinder, said valve apparatus comprising a chamber having opposite end portions, a central portion, and steam inlet ports communicating with the cylinder adjacent opposite extremities of the stroke of said piston, the end portions and the central portion each having a separate steam outlet, a piston valve rod arranged for reciprocal movement in the chamber, bushing means in said chamber having opposite end portions, a central portion longitudinally spaced ports therethrough, one of said ports being in communication with one of the inlet ports and with an end portion of the chamber and another port being in communication with said central portion of the chamber, cylindrically-shaped exhaust valves mounted in spaced relationship to one another on the piston valve rod and in spaced relationship to the opposite end portions to move therewith and respectively slidably engage one of said bushings in a fluid-tight manner, the valves having a concave peripheral portion, said peripheral portion being of such length that when the valves are in their closed position the concave portion overlaps said one of the spaced ports only and when the valves are in their open position said one port is in communication with one of the end portions of the chamber and with said other port of the longitudinally shaped ports through said concave peripheral portion of the valve so that steam will flow into the end portions and intermediate portion of the chamber from the inlet ports.

8. Valve apparatus for exhausting steam from the cylinder of a reciprocal steam engine, locomotive or the like having a reciprocating piston in said cylinder, said valve apparatus comprising a chamber having opposite end portions, a central portion, and steam inlet ports communicating with the cylinder adjacent opposite extremities of the stroke of said piston, a piston valve rod arranged for reciprocal movement in the chamber, bushing means in said chamber adjacent opposite ends thereof and having a plurality of longitudinally spaced ports, one of said spaced ports being in communication with a steam inlet port and an end portion of the chamber and at least two other of said longitudinally spaced ports being in communication with said central portion of the chamber, cylindrically-shaped exhaust valves mounted in spaced relationship to one another on the piston valve rod to move therewith and respectively slidably engage one of said bushings in a fluid-tight manner, the valves having passages so arranged that when the valves are in closed position the valve overlaps said one of the spaced ports and the passages are out of communication with the inlet ports and when the valves are in their open position said one port is in communication with an end portion of the chamber and with the other ports of the longitudinally spaced ports through said valve passages so that steam will flow from the inlet ports into the end portions and central portion of the exhaust chamber.

9. Valve apparatus for admitting steam to the cylinder of a reciprocal steam engine, locomotive or the like having a reciprocating piston in said cylinder, the valve apparatus comprising a cylindrical chamber having a peripheral wall with a longitudinal passage therein communicating with opposite end portions of the chamber, steam inlet means in communication with said passage and with the chamber intermediate the opposite ends thereof, the cylinder having steam outlet ports, said outlet ports communicating with the cylinder adjacent opposite extremities of the stroke of said piston, a piston valve rod arranged for reciprocal movement in the chamber, bushing means in said chamber adjacent opposite ends thereof and having a plurality of longitudinally spaced ports therethrough, one of said spaced ports being in communication with a steam outlet port and the central portion of the chamber and at least two other of said longitudinally spaced ports being in communication with an end portion of the chamber, cylindrically-shaped admission valves mounted in spaced relationship to one another on the piston valve rod to move therewith and respectively slidably engage one of said bushings in a fluid-tight manner, the valves having passages so arranged that when the valves are in closed position the valves overlap said one of the spaced ports and the passages are out of communication with the outlet ports and when the valves are in their open position said one port is in communication with the intermediate portion of the chamber and with said other ports of the longitudinally spaced ports through said valve passages so that steam will flow from the end portions and from said intermediate portion of the chamber to said outlet ports.

75 said outlet ports communicating with the cylin-

der adjacent opposite extremities of the stroke of said piston, a piston valve rod arranged for reciprocal movement in the chamber, bushing means in said chamber adjacent opposite ends thereof and having a plurality of longitudinally spaced ports therethrough, an intermediate port of said spaced ports being in communication with a steam outlet port and with the central portion of the chamber through at least one of said spaced ports at the side thereof adjacent the central portion of the chamber and at least two other of the longitudinally spaced ports at the side of the intermediate port adjacent an end portion of the chamber being in communication with said end portion of the chamber, cylindrically-shaped admission valves mounted in spaced relationship to one another on the piston valve rod to move therewith and respectively slidably engage one of said bushings in a fluid-tight manner, the valves having passages so arranged that when the valves are in closed position a portion of the valves overlap said intermediate port and said at least one port and the passages are out of communication with said outlet port and when the valves are in their open position the intermediate port is in communication with the intermediate portion of the chamber through said at least one port and through a passage in the valve and with said other ports of the longitudinally spaced ports through said valve passages so that steam will flow from the end portions and from said intermediate portion of the chamber to said outlet ports.

10. Valve apparatus for exhausting steam from the cylinder of a reciprocal steam engine, locomotive or the like having a reciprocating piston in said cylinder, said valve apparatus comprising a chamber having opposite end portions, a central portion, and steam inlet ports communicating with the cylinder adjacent opposite extremities of the stroke of said piston, a piston valve rod arranged for reciprocal movement in the chamber, bushing means in said chamber adjacent opposite ends thereof and having a plurality of longitudinally spaced ports, an intermediate port of said spaced ports being in communication with a steam inlet port and with an end portion of the chamber through at least one of said spaced ports at the side thereof adjacent said end portion of the chamber and at least two other of the longitudinally spaced ports at the side of the intermediate port adjacent the central portion of the chamber being in communication with said central portion, cylindrically-shaped exhaust valves mounted in spaced relationship to one another on the piston valve rod to move therewith and respectively slidably engage one of said bushings in a fluid-tight manner, the valves having passages so arranged that when the valves are in closed position a portion of the valves overlap said intermediate port and said at least one port and the passages are out of communication with said inlet port and when the valves are in their open position the intermediate port is in communication with the end portions of the chamber through said at least one port and through a passage in the valve and with the other ports of the longitudinally spaced ports through said valve passages so that steam will flow from the inlet ports into the end portions and central portion of the exhaust chamber.

11. A piston valve for bringing a port into communication with at least two other ports at one side of the first-mentioned port, said valve

comprising a cylindrically-shaped body member, means for reciprocating said body member, the body member being of a length to extend from a point substantially centrally of the first-mentioned port to a point slightly beyond the one of said at least two other ports furthest removed from said one port when the valve is in opened position, said body member having a central passage forming portion of lesser diameter than the outside diameter of the valve and communicating with the first-mentioned port and said furthest removed port when the valve is opened, and a port closing member movable with said valve and so positioned as to control a port intermediate the first-mentioned port and said furthest removed port so that the intermediate port is in communication with the passage forming portion when the valve is in opened position and is closed from communication with said passage portion when the valve is closed.

12. A piston valve for bringing an intermediate port into communication with ports on opposite sides thereof, at least two ports being on one side of the intermediate port and at least another port being on the opposite side of the intermediate port, the at least two ports being in communication with one another through an uncontrolled passage and the intermediate port being in communication with said at least one port through another uncontrolled passage, said valve comprising a cylindrically-shaped body member, means for reciprocating said body member, the body member being of a length to extend from a point just beyond the one of said two ports furthest from the intermediate port to a point at the side of said at least one port nearest the intermediate port when the valve is in opened position, and port control sections positioned on the body member to control said at least one port and the port of said at least two ports intermediate the intermediate port and said furthest port, the body member also having controlled passages therein, one of said passages being in communication with the intermediate port and said at least two ports and the other of said passages being in communication with the intermediate port and the end of the valve adjacent said at least one port, the port control sections being movable with the valve and so arranged that the ports controlled thereby are opened so that the intermediate port is in communication with said passages and the ports and said end of said valve when the valve is in an opened position and are closed by said sections when the valve is in closed position.
